UNITED STATES PATENT OFFICE.

LORENZO C. MATTESON, OF WATERTOWN, NEW YORK.

SASH-WEIGHT.

SPECIFICATION forming part of Letters Patent No. 369,952, dated September 13, 1887.

Application filed February 3, 1887. Serial No. 226,464. (No model.)

To all whom it may concern:

Be it known that I, LORENZO C. MATTESON, a citizen of the United States, residing at Watertown, in the county of Jefferson and State of New York, have invented certain new and useful Improvements in Sash-Balances; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

Figure 1 is a side elevation of a sash-weight embodying my invention. Fig. 2 is an inner side elevation of one of the weight-sections. Fig. 3 is a transverse section of the same sash-weight, and Fig. 4 is an end view of the same. Fig. 5 is an edge view of a modified form of sash-weight, and Fig. 6 is an end view thereof. Fig. 7 is a detail section showing a portion of the sash-weight and the pulley, and illustrating the method of journaling the pulley in the weight.

My invention relates to sash-balances. The object of my improvement is to provide a sash-weight carrying a pulley over which the sash-cord passes, and which is capable of being inserted through the ordinary pocket in window-frames which are provided with sash-balances.

A further object is to make the weight in two parts, so as to inclose the sash-cord pulley within, whereby certain advantages accrue, all of which will be fully described in detail, and the points of novelty then set forth in the claim.

In the drawings, *a* represents a sash-weight, made in two parts, *b* and *c*.

d is a pulley inclosed within the sash-weight.

e is a bolt which holds the two parts together.

ff are lugs or spurs formed on the half-section *c* of the weight, and *g* is a corresponding depression formed on half *b*. They interlock when the two halves are placed together and bolted, and prevent any displacement of the sections.

h is the sash-cord.

i i are studs or short journals, upon which the pulley *d* turns.

k is the opening within the weight within which the pulley *d* turns.

ll are openings leading from the space *k* on either side through the top of the weight, and through which the sash-cord *h* passes.

m is that part of the casting immediately above the opening *k* and between the openings *ll*.

The two sections *b c* of the weight may be of equal size, dividing the weight through the center, as shown in Figs. 1, 2, 3, and 4, or the contacting faces of the two halves may be cut in a diagonal line through the weight, as shown in the end view, Fig. 6, and edge view, Fig. 5, or in any other known way whereby access may be had to the opening *k* to remove the pulley *d*.

The pulley *d* may have conically-shaped cavities, within which the studs *i i* enter, Fig. 3; or pulley *d* may have the projections or studs *i* cast upon it, as shown in Fig. 7, and a bearing made for them in the sections *b c*.

The bolt *e* and the opening through the weight which receives it may be of any known construction.

There may be more or less number of lugs *f* and recesses *g*, if desirable, and they may be placed on other parts of the weight-sections.

The openings *ll*, through which the sash-cord passes, may be of different shapes. Figs. 4 and 6 illustrate two forms.

My improved sash-weight is designed more particularly in connection with that class of sash-balances which employ a single cord on either side to balance both sashes.

To apply my weight to the sash-cord, I first remove the bolt or key *e* and take apart the two sections *b* and *c*. The pulley *d* is then taken out and a loop of the sash-cord *h* placed within the openings *ll* and receptacle *k*, the pulley replaced, and the two sections then rebolted together.

In my improved sash-weight, made in two parts and of the relative width and thickness shown, I am enabled to quickly adjust it upon the cord and insert it through the usually-shaped pocket made in window-frames.

Having described my invention, what I

claim as new, and desire to secure by Letters Patent, is—

A sash-weight made in two parts, provided with a pulley-holding receptacle, a bolt for uniting the parts, lugs for preventing the displacement of the sections, and a pulley journaled within the receptacle, all in combination, substantially as herein described.

In testimony whereof I affix my signature in presence of two witnesses.

LORENZO C. MATTESON.

Witnesses:

J. O. HATHWAY,
P. NORTON.
